Emery, Parker.

DESIGN

FACE-PLATE or DOOR-LOCK

PATENTED
SEP 28 1869

Inventor.
Emery Parker.

United States Patent Office.

EMERY PARKER, OF NEW BRITAIN, CONNECTICUT.

Design No. 3,673, dated September 28, 1869.

DESIGN FOR THE FACE-PLATE OF A LATCH.

The Schedule referred to in these Letters Patent and making part of the same.

I, EMERY PARKER, of New Britain, in the county of Hartford, and State of Connecticut, have invented and produced a new and original Design for the Face-Plate of a Lock or Latch, of which the following is a specification.

The accompanying drawing shows a front elevation of my design.

A designates the bolt, and B the latch-mortises.

When the lock is placed in its mortise in the door-stile, and the door opened, the plate is exposed to view.

To give an ornamental effect to the plate, I border its edge with one or more channels *a*, sunk in the plate, which give the appearance of a sunken panel, although not such.

I also prefer to border the bolt and latch-mortises, A and B, with similar channels *a*.

If desired, the spaces between the channels and the mortises may be filled in with ornamental scroll-work.

What I claim as new, and desire to secure by Letters Patent, is—

The design for the face-plate of a lock or latch, which consists in bordering the edge of the plate, or the edge of the plate and the bolt and latch-mortises, with sunken channels *a*, substantially as herein shown and described.

EMERY PARKER.
